UNITED STATES PATENT OFFICE

EDWARD ROY ALLING, OF KENMORE, NEW YORK, ASSIGNOR TO RICE & ADAMS CORPORATION, OF BUFFALO, NEW YORK

CRATE OR CASE

Application filed February 24, 1928. Serial No. 256,714.

This invention relates to crates, cases and the like which are built up of wooden side and end slats or boards connected together at the upright corners of the case by metal corner connectors, fittings or reinforcements, and more particularly to bottle crates of this sort which are used, for example, for handling milk bottles, and are ordinarily provided with partition wires or strips which divide the 5 crate into a plurality of pockets each adapted to receive one bottle, whereby the bottles are separated and held from shifting about in the crate and from contacting with each other.

The object of the invention is to provide a 15 strong, durable and practical crate or case of this sort, which embodies various improvements and has various advantages hereinafter described and particularly set forth in the claims.

20 In the accompanying drawings:

Fig. 1 is a side elevation of a milk bottle crate embodying my invention.

Fig. 2 is an end elevation thereof.

Fig. 3 is a plan view thereof.

25 Fig. 4 is a longitudinal, sectional elevation thereof on an enlarged scale.

Fig. 5 is a fragmentary, transverse, sectional elevation, enlarged, on line 5—5 of Fig. 4, showing the stay or brace device for the 30 partition wires.

Fig. 6 is a sectional elevation thereof on line 6—6, Fig. 7.

Fig. 7 is a transverse, sectional elevation of the crate on line 7—7, Fig. 4.

35 Fig. 8 is a fragmentary, sectional elevation thereof, on an enlarged scale, on line 8—8, Fig. 2.

Fig. 9 is an inside perspective view of one 40 of the corner connections of the crate, showing by full and broken lines two wooden slats, one inserted in one of the pockets of the connector and the other removed.

Fig. 10 is a fragmentary section through 45 one of the corner connections on line 10—10, Fig. 11.

Fig. 11 is a fragmentary, horizontal section on an enlarged scale on line 11—11, Fig. 10.

50 Fig. 12 is a similar horizontal, sectional view on line 12—12, Fig. 10.

Fig. 13 is a vertical section on an enlarged scale on line 13—13, Fig. 7.

Fig. 14 is a vertical section on an enlarged scale on line 14—14, Fig. 4.

The upright walls of the crate or case are 55 formed by horizontal side slats or boards 15 and end slats or boards 16, each wall being preferably composed of a plurality of the slats 15 and 16 arranged on edge vertically one above the other, the ends of these side and 60 end slats being connected together by corner connectors or reinforcements at the four upright corners of the crate.

Each of these corner connectors is formed by an outer angle plate 17 and an inner angle 65 plate 18 which are preferably formed from sheet metal. The two flanges of the outer angle plate 17 extend vertically flat against the outer faces of adjacent end and side slats of the crate, and the upper ends of the flanges of 70 the outer angle plate 17 are preferably bent inwardly, as indicated at 19, over and against the upper edges of the top slats of the crate. The lower end of the outer angle plate 17 is slotted to form reduced extensions 20, see 75 Fig. 9, which are bent inwardly under the lower edges of the adjacent bottom slats and then upwardly at the inner sides of the bottom slats. Both the upper and lower end portions of the outer angle plate 17 are pref- 80 erably cut so that the indent extensions 19 and 20 thereof will meet in miter joints, as indicated at the top in Fig. 9. The inner angle plate 18 has vertical flange portions 21 which extend vertically at an angle to each 85 other flat against the inner vertical faces of the slats of the adjacent end and side of the crate, and which portions 21 are connected by horizontally bent, preferably U-shaped portions 22 which extend outwardly toward 90 the flanges of the outer angle plate 17 and are secured thereto, as by rivets 23, thereby connecting the inner and outer angle plates rigidly together and forming a plurality of spaced 95 pockets 24 in which the ends of the adjacent side and end slats are adapted to fit, and by which the slats are held in place. The inner angle plate 18 having this form, can be conveniently formed from a sheet metal plate 100 which is bent to form the U-shaped transverse

portions 22, and is slit longitudinally on its median line 22 α through these U-shaped portions, after which the plate thus bent, is bent longitudinally along its median line 22 α to 5 form the flange portions 21 which bear against the inner faces of the slats. After the ends of the slats 15 and 16 have been inserted in the pockets 24, rivets or fasteners 25 are passed through registering holes 26 in 10 the flanges of the inner and outer angle plates 17 and 18 and through the top slats 15 and 16, and riveted at their ends, thus fastening the top slats to the corner connectors. In 15 like manner, the bottom slats are secured in the bottom pockets of the corner connectors by rivets or the like 27 which are passed through registering holes in the flanges of the inner and outer angle plates 17 and 18 and through holes in the ends of the bottom 20 slats and are riveted at their ends. The rivets 27 for the bottom slats also preferably pass through the upbent, bottom end extensions 20 of the outer angle plate so that the same rivets also secure these upbent extensions in place.

The corner connectors at the four corners of the crate are thus secured together through the medium of the top and bottom slats, and the intermediate slats are retained 30 in place by fitting in the intermediate pockets 24 of the corner connectors, but only the top and bottom slats need to be riveted or permanently secured to the connectors. Therefore, in the event of any of the slats of the crate, 35 being broken, it is only necessary to cut the rivets at the upper or lower ends of the corner connectors to permit the separation of the parts of the crate and the insertion of new slats to replace the broken ones. This enables quick and comparatively inexpensive 40 repairs to the crate.

In the crate shown, the slats are wider vertically than the pockets 24 and are formed with end tenons 28 of a size to enter the 45 pockets. Therefore, the slats of each wall can meet edge to edge to form a solid wall, or if desired, the slats can be made no wider vertically than the pockets, in which case the walls of the crate will be formed by slats 50 separated by open spaces. Also the corner connectors can be made with pockets 24 of different heights and in different numbers, thus adapting the walls of the crate to be built up of different numbers of slats which 55 may either abut edge to edge or be spaced apart desired distances.

30 and 31 represent protecting shoes for the lower edges of the crate. Each of these shoes consists of a channel shaped metal strip 60 which embraces the bottom edge of one of the lower slats of the crate, extending across the edge and a short distance up along the inner and outer faces of the slat. The channel shoe is secured to the crate by rivets 32 passing 65 transversely through the slat and through

registering perforated lugs 33 extending upwardly from the inner and outer flanges of the channel. At their ends, the side walls of the channel shoes extend in between the slats and inner and outer angle plates 17 and 18 of the corner connectors, and are provided with end perforated lugs 34 through which pass the rivets 27 which secure the bottom slats in the corner connectors. Thus, the shoes at the ends and sides of the crate are 70 riveted to and tie together the metal connectors at the four corners of the crate and thereby form a continuous metal tie or binder extending completely around the lower end 75 of the crate. The bottom walls of the channel shoes are preferably cut away at their ends at 35, see Fig. 13, and abut against the edges of the horizontal parts of the inbent extensions 20 of the outer angle plates 17 80 of the corner connectors. The bottom walls of the shoes and the inbent extensions 20 of the corner plates 17 are thus flush with each other at the bottom edges of the crate and provide a metal surface extending completely 85 around the bottom edge of the crate adapted 90 to take the wear incident to shoving or dragging the crate along on the floor or pavement. Preferably, the bottom slats 15 and 16 are rabbeted or recessed a 36 to receive the outer 95 flanges of the channel shoes and their perforated lugs, so that the outer, vertical faces of the shoes will lie flush with the outer faces 100 of the slats of the crate.

The crate is preferably provided, as usual in milk bottle crates, with corner lugs 40 100 which are secured in the corners of the crate at its upper end and project above the top edge of the crate for the purpose of entering the bottom of the next crate above when stacking the crates one upon the other, to hold the crates in vertical alinement. The corner lugs 40 shown preferably consist of sheet metal stampings and are secured in the corners of the crate by rivets 25 which connect the upper ends of the corner connectors 105 to the upper slats of the crate, and the corner irons 40 are preferably recessed to receive the upper ends of the inner plates 18 of the corner connectors so that the lugs 40 can fit flat 110 against the inner faces of the top slats of the crate at the upper edges thereof, as shown in Fig. 7.

50 represent the usual bottom wires which extend lengthwise of the crate near its bottom and are secured to the ends of the crate, the wires 50 thus forming bottom supports for the bottles. Above the bottom wires 50 are the usual longitudinal partition wires 51 and transverse partition wires 52, preferably arranged in upper and intermediate sets. 115 The longitudinal wires may be secured in any suitable way to the ends of the crate, and the transverse wires may be secured to the sides of the crate in any suitable manner. The bottom wires 50 are preferably held parallel 120 to the bottom edge of the crate. The wires 51 and 52 are secured to the ends of the crate in any suitable manner, and the wires 51 and 52 are secured to the sides of the crate in any suitable manner. The bottom wires 50 are preferably held parallel 125 to the bottom edge of the crate. The wires 51 and 52 are secured to the ends of the crate in any suitable manner, and the wires 51 and 52 are secured to the sides of the crate in any suitable manner. The bottom wires 50 are preferably held parallel 130 to the bottom edge of the crate. The wires 51 and 52 are secured to the ends of the crate in any suitable manner, and the wires 51 and 52 are secured to the sides of the crate in any suitable manner.

in the intended spaced relation and prevented from being bent between their ends by a transverse spacing bar or strip 54, see Fig. 7, which is bent to provide seats 55, in which 5 the bottom wires rest, and is bent upwardly at 56 between spaced pairs of the bottom wires 50, as indicated in Fig. 7. A transverse securing wire 57 is threaded through holes in the upbent portions 56 of the spacing strip 10 54, above the bottom wires 50. This wire retains the bottom wires in the seats in the spacing strip 54 and the wire 57 passes through down-bent ends of the spacing strip 54 and is secured in the sides of the crate, 15 thereby securing the spacing strip in place so that the latter firmly holds the bottom wires and prevents the bending or spreading of the same.

60 represents two stays or braces for tying together and bracing the bottom and partition wires. Each of these ties or braces 20 60 preferably consists of an upright, flat metal strip having its lower end bent or looped around the transverse wire 57 and passing 25 through a slot 61, Figs. 5 and 6, in the spacing strip 54, and has its upper end bent or looped around one of the top, transverse partition wires 52. One of the top longitudinal partition wires 51 passes through registering holes 30 62 in the looped upper end of the stay 60 beneath the top, transverse wire 52 in the top loop of the stay. Between its ends, the stay 60 is provided with a hole 63 through which one of the intermediate, longitudinal partition 35 wires 51 passes, and adjacent this hole the stay is slit longitudinally at 64, see Fig. 5, and the parts of the stay at opposite sides of the slit are bent in opposite directions to form an eye 65, Fig. 6, through which one of the 40 intermediate, transverse partition wires 52 passes. The stay or tie 60 is thus securely fastened at its lower end to the transverse wire 57 and bottom wires 50, and at its upper end to the intersecting, longitudinal and 45 transverse partition wires 51 and 52, and between its ends is connected to the intermediate, longitudinal and transverse partition wires 51 and 52. Thus, these several 50 wires are securely tied together and a rigid connection or brace formed between the same, which prevents bending or deflection of the wires, and forms a very strong connection between them.

Milk men in handling these crates, frequently lift them when filled with bottles, by 55 the partition wires, and unless the wires are properly braced and tied together between their ends, they are soon bent out of shape so as not to properly perform their intended 60 function. The above described stay and brace prevents such deflection or displacement of the wires, and the wires or crate cannot be injured by handling or carrying the crate by means of the wires.

65 The end walls of the crate are preferably

provided with the usual hand holes 70 for the insertion of the fingers in carrying the crate. In large dairies and milk distributing plants, stacks of these crates filled with bottles are often moved about on two-wheeled hand trucks, and in loading the trucks, it is common practice in some plants to insert a hook in the hand hole of one of the crates of the stack to tilt the stack over onto the truck when loading the truck. These hooks are apt to break or tear the wood of the crate around the hand holes 70. In order to prevent this injury and wear on the crates, a wear plate 71 is preferably secured on the inside of the end wall of the crate above each hand hole. This 75 wear plate may be riveted or secured to the wall of the crate in any suitable manner, and its lower edge 72 is preferably bent outwardly to fit and conform to the rounded or curved edge of the hand hole so that the wear plate 80 presents a smooth, rounded edge which will not cut or injure the hands of the person carrying the crate. Nevertheless, the wear plate forms a metal surface adapted to be engaged by the hook in loading the crates 85 onto the truck, and not only prevents injury to the slats, but also prevents the tearing or splitting of the wood so that the hand of the person handling the crate is not apt to be injured by the rough surface of splinters of 90 the wood.

I claim as my invention:

1. A case comprising side and end walls, and having pairs of longitudinal bottom wires, a horizontal spacing strip for supporting said bottom wires including a seating part extending beneath each pair of said wires and having seats therefor, said strip also having upbent parts projecting between said pairs of wires and connecting said seating parts, and a horizontal securing wire extending between and fixed to opposite walls of said case and which passes through holes in said spacing strip so as to extend under said upbent parts thereof and over said seating parts against said bottom wires for holding the same securely in said seats. 100

2. A case comprising side and end walls, and having pairs of longitudinal bottom wires, a horizontal spacing strip for supporting said bottom wires including a seating part extending beneath each pair of said wires and having seats therefor, said strip also 105

having upbent parts projecting between said pairs of wires and connecting said seating parts, a horizontal securing wire extending

between and fixed to opposite walls of said case and which passes through holes in said 110

spacing strip so as to extend under said upbent parts thereof and over said seating parts against said bottom wires for holding

the same securely in said seats. 115

3. A case comprising side and end walls, and having pairs of longitudinal bottom wires, a horizontal spacing strip for supporting said bottom wires including a seating part extending beneath each pair of said wires and having seats therefor, said strip also 120

having upbent parts projecting between said pairs of wires and connecting said seating parts, a horizontal securing wire extending

between and fixed to opposite walls of said case and which passes through holes in said 125

spacing strip so as to extend under said upbent parts thereof and over said seating parts against said bottom wires for holding

the same securely in said seats, and said spacing strip having end portions engaging said 130

opposite end walls and having holes therein

through which said securing wire passes for securing said strip in place in said case.

3. A case comprising side and end walls, longitudinal and transverse partition wires connecting said end and side walls respectively above said bottom wires, a horizontal spacing strip for supporting said bottom wires including a seating part extending beneath each pair of said wires and having seats therefor and having upbent parts projecting between said pairs of wires and connecting said seating parts, a horizontal securing wire extending between and fixed to opposite walls of said case and which passes through holes in said spacing strip and extends under said upbent parts thereof and over said seating parts against said bottom wires for holding them in their seats, and a stay strip having its upper end secured to a longitudinal and a transverse partition wire at their intersection and having its lower end extending downwardly through said spacing strip and looped about said securing wire with said strip engaging upon said loop, whereby said bottom wires, said securing wire and said spacing strip are braced and prevented from downward deflection.

E. ROY ALLING.
